INVENTOR,

Edgar L. Williams,
By L. M. Thurlow, ATTY.

UNITED STATES PATENT OFFICE.

EDGAR L. WILLIAMS, OF PEORIA, ILLINOIS.

DESIGN FOR A GAME-COUNTER.

SPECIFICATION forming part of Design No. 30,158, dated February 7, 1899.

Application filed December 8, 1898. Serial No. 698,679. Term of patent 31 years.

To all whom it may concern:

Be it known that I, EDGAR L. WILLIAMS, a citizen of the United States, residing at Peoria, in the county of Peoria, and State of Illinois, have invented a certain new and useful Design for a Game-Counter; and I do hereby declare that the following is a full, clear, and exact description of the invention, which will enable others skilled in the art to which it appertains to make and use the same.

The appended drawings show several views of a game-counter. It is used in playing various games of skill by snapping or forcing a picked counter against others of its kind, the playing being done upon a smooth plane surface.

Figure 1 is a plan view of the counter, showing its peculiar ring form and concaved

surface. Fig. 2 is a cross-section of the same in elevation, showing concaves and hollow 20 interior. Fig. 3 is a sectional view of Fig. 1.

The counter consists of a ring having a concaved upper and lower surface, while the wall thereof is convexed on the outer or striking surface and is concaved in the interior. The 25 ring is hollowed out and leaves the annular ribs or webs at the top and bottom, as shown.

I claim—

The design for a game-counter substantially as herein shown and described. 30

In testimony whereof I affix my signature in presence of two witnesses.

EDGAR L. WILLIAMS.
